(57) **CLAIM**

An ornamental design for a multi-positional chair, as shown and described.

DESCRIPTION

FIG. 1 is a top, front perspective view of a first embodiment of the multi-positional chair shown in a first position in which the seat and back are in a raised position;

FIG. 2 is a bottom, rear perspective view thereof;

FIG. 3 is a side elevational view thereof;

FIG. 4 is a top, front perspective view of a second embodiment of the multi-positional chair shown in a first position in which the seat and back are in a raised position; and,

FIG. 5 is a bottom, rear perspective view thereof.
